(57) **CLAIM**

The ornamental design for a vessel keeper for endoscopic harvester, as shown and described.

DESCRIPTION

FIG. 1 is a perspective view of a vessel keeper for endoscopic harvester embodying our design.

FIG. 2 is a top plan view thereof.

FIG. 3 is a bottom plan view thereof.

FIG. 4 is a side elevational view thereof.

FIG. 5 is a side elevational view thereof.

FIG. 6 is a rear elevational view thereof; and,

FIG. 7 is a front elevational view thereof.

The broken lines in the drawings depict portions of the vessel keeper for endoscopic harvester that form no part of the claimed design.
